Attorney

UNITED STATES PATENT OFFICE.

JOHN A. HOLMES, OF MILWAUKEE, WISCONSIN.

VELOCIPED.

SPECIFICATION forming part of Letters Patent No. 447,542, dated March 3, 1891.

Application filed December 13, 1890. Serial No. 374,570. (No model.)

To all whom it may concern:

Be it known that I, JOHN A. HOLMES, a citizen of the United States, and a resident of Milwaukee, in the county of Milwaukee, and in the State of Wisconsin, have invented certain new and useful Improvements in Bicycles and Analogous Vehicles; and I do hereby declare that the following is a full, clear, and exact description thereof.

10 My invention consists in certain peculiarities of construction and combination of parts to be hereinafter described, with reference to the accompanying drawings, and subsequently claimed.

15 In the drawings, Figure 1 represents a side elevation of a portion of a bicycle constructed according to my invention; Fig. 2, a plan view, partly in horizontal section, on line 2 2 of the preceding figure; Fig. 3, a detail view in front 20 elevation and transverse section; and Fig. 4, a section on line 4 4 of Fig. 3.

Referring by letter to the drawings, A represents the front fork of a bicycle, and pivoted to each furcation of this fork at or near 25 the lower end of the same is a hanger B for the front axle C, the construction thus far described being well known in the art to which my invention relates.

As is also usual in the art, each furcation 30 of the fork A is provided with a laterally-extended foot-rest for the rider when coasting with the vehicle, the foot-rest in this instance being one that consists of a headed rod D, having its inner end screw-threaded and 35 passed through the adjacent fork-furcation to engage a clamping-nut E, and a corrugated rubber sleeve F, arranged on the rod inside of the head of the latter. Ordinarily, the rubber sleeve F fills the entire space between 40 the rod-head and outer side of the adjacent fork-furcation; but in the present instance I prefer to make said sleeve shorter than usual and interpose a casting G between it and said fork-furcation, this casting being a plate provided with an opening for engagement with 45 the rod D, and having inwardly-extended ears b c above and below the opening, as is clearly illustrated in Figs. 3 and 4.

Slipped onto the rod D to rest upon the 50 lower ear c of the casting G is the upper loop d of a spring H, and the lower loop e of this

spring engages the axle C, and is held thereon by means of a nut f, as clearly illustrated in Figs. 1 and 2.

In order to obtain the most satisfactory results I prefer to make the spring H in the form of a compound curve and of a rod so bent as to form two such curves, one within the other, the ends of the spring-rod being united by welding or otherwise, to thus produce a device of the form above described, and clearly illustrated in Fig. 1.

The upper ear b of the casting G engages the adjacent loop d of the spring H, and when pressure comes on and off this spring the latter and said casting are free to oscillate on the rod D of the foot-rest.

By the employment of springs constructed and arranged as set forth in the foregoing the wheel (shown by the dotted lines, Fig. 1) 70 is held down to its work, and the vibration that would otherwise come upon the steering-fork and handle-bar of the vehicle is absorbed.

Having thus fully described my invention, what I claim as new, and desire to secure by 75 Letters Patent, is—

1. In a bicycle or analogous vehicle, the combination of a fork, axle-hangers pivoted to the furcations thereof, and an endless spring connected to each fork-furcation and opposed 80 to pivotal movement of the adjacent hanger, substantially as set forth.

2. In a bicycle or analogous vehicle, the combination of a fork, axle-hangers pivoted to the furcations thereof, and endless springs 85 having their upper extremities connected to the fork-furcations and their lower extremities connected to the axle, substantially as set forth.

3. In a bicycle or analogous vehicle, the 90 combination of a fork, axle-hangers pivoted to the furcations thereof, and endless springs connected to the fork-furcations and arranged to oppose pivotal movement of the hangers, each spring consisting of a rod bent to form 95 two curves, one within the other, and united at its ends, substantially as set forth.

4. In a bicycle or analogous vehicle, the combination of a fork having the furcations thereof provided with laterally-extended supports, plates arranged on the rod and provided with ears, axle-hangers pivotally connected 100

to the fork-furcations, and springs having their upper extremities engaging said supports between the plate-ears and their lower extremities arranged to oppose pivotal movement of said hangers, substantially as set forth.

5. In a bicycle or analogous vehicle, the combination of a fork having the furcations thereof provided with laterally-extended supports, plates arranged on the rods and provided with ears, axle-hangers pivotally connected to the fork-furcations, and endless springs having their upper extremities engaging said supports between the plate-ears and their lower ends arranged to oppose pivotal movement of said hangers, substantially as set forth.

6. In a bicycle or analogous vehicle, the combination of a fork having the furcations thereof provided with foot-rests, axle-hangers ²⁰ pivotally connected to the fork-furcations, and springs connected to the foot-rests and arranged to oppose pivotal movement of said hangers, substantially as set forth.

In testimony that I claim the foregoing I ²⁵ have hereunto set my hand, at Milwaukee, in the county of Milwaukee and State of Wisconsin, in the presence of two witnesses.

JOHN A. HOLMES.
